UNITED STATES PATENT OFFICE.

WILBUR F. MAISH, OF WARSAW, INDIANA.

SPLIT PULLEY.

SPECIFICATION forming part of Letters Patent No. 426,292, dated April 22, 1890.

Application filed November 19, 1889. Serial No. 330,869. (No model.)

To all whom it may concern:

Be it known that I, WILBUR F. MAISH, a citizen of the United States, residing at Warsaw, in the county of Kosciusko and State of Indiana, have invented certain new and useful Improvements in a Split-Band Pulley, of which the following is a full, clear, and exact description, that will enable others to make and use the same, reference being had to the accompanying drawings, forming a part of this specification.

This invention relates to improvements in split pulleys; and it consists of certain novel features in the construction, combination, and arrangement of the different parts, as will be hereinafter set forth.

Figure 1 is a side elevation of a pulley embodying my improved features; Fig. 2, a transverse section in plane 2, Fig. 1, looking in the direction indicated by the arrow; Fig. 3, a diametrical section in plane 3, Fig. 2; and Fig. 4, a detached end view of the separable or split sleeve.

Referring to the drawings, A represents the rim of the pulley, B the hub, C the arms on one side, and D the companion bracing-arms located on the opposite side of the hub. The rim consists of a number of sections a , laid up in the usual manner and secured together by means of some adhesive composition and the dowel-pins a' . The rim is in two parts $a^2 a^3$, united on the line a^4 , and secured together by the angle-plates b and the bolts b' , passing through the same.

The hub B consists of the two rectangular members $d d'$, loosely inclosing the separable sleeve E and secured together by a number of clamping-bolts F, arranged relatively as shown.

The continuous bracing-arms C D are each composed of a thin strip of steel rectangular in cross-section, the central parts g of which lie flat against the respective sides of the hub members, as illustrated in Figs. 1 and 3, and are rigidly secured thereto by the clamping-bolts F, passing through the same. At the point where the arm part proper leaves the hub they are given a twist, as at g' , so as to present their thin edges in the direction of

the axis of motion, and leaving the space 50 between the arms, as shown in Fig. 2, thereby offering less resistance to the atmosphere, and consequently making a lighter-running pulley. The arm is also stronger, as the strain is edgewise instead of flatwise, thus 55 allowing the use of a lighter arm. The part g^2 of the arms extends from the hub to the rim at an oblique angle with reference to the axis.

The arms C D gradually diverge from the 60 hub outwardly, so that the terminal ends mortised in the rim are wide apart, thus embracing more of the circumferential surface than if they were straight, and also having better bracing qualities and affording greater 65 strength to the structure. The ends of the arms inserted in the rim are secured in place by the screws g^3 .

The sleeve E is divided longitudinally on a diagonal line h with reference to the center of axis, so as to provide the beveled edges $h' h'$ (see Fig. 4) for the purpose of imparting a wedge-like action when the pulley is clamped on the shaft, a little space h^2 being left between the adjacent faces of the 75 hub members to facilitate the clamping and wedging feature.

Having thus described my invention, what I claim as new, and desire to secure by Letters Patent, is—

1. The combination, in a split pulley, of the continuous bracing-arms, each consisting of a thin strip of metal having the central flat part rigidly secured to the hub and the arm parts twisted to bring the edge parts at right 85 angles thereto and diverging at an oblique angle with reference to each other, and having the terminal ends permanently fixed in the rim, substantially as described.

2. The combination, in a split pulley, of 90 the rim, the hub members, the continuous twisted bracing-arms, the flat central parts whereof are rigidly secured to opposite sides of the hub members, the arm part extending at an oblique angle therefrom and terminating in the rim, and the clamping-bolts passing through the arms and hub, substantially 95 as described.

3. The combination, in a split pulley, of the rim, the continuous twisted bracing-arms, the hub members, the split sleeve divided in a diagonal plane with reference to the axis, and the clamping-bolts passing through said arms and hub members, substantially as described.
4. The combination, in a split pulley, of

a separable sleeve divided in a diagonal plane with reference to the axis of motion, substantially as described.

WILBUR F. MAISH.
